TREATMENT OF HYDROCARBONS

Herman S. Bloch, Chicago, Ill., assignor to Universal Oil Products Company, Chicago, Ill., a corporation of Delaware

No Drawing. Application August 7, 1941,
Serial No. 405,787

12 Claims. (Cl. 260—683.5)

This invention relates to the treatment of hydrocarbons of essentially straight-chain structure, to increase their degree of branching and thus produce substantial yields of their isomeric counter-parts.

The invention is more specifically directed to the isomerization of normal paraffin hydrocarbons beginning with normal butane as the only gaseous representative of the class capable of isomerization and extending to the treatment of normally liquid normal paraffin hydrocarbons of considerably higher molecular weight although the precise effect of the treatment to be hereinafter specified will vary considerably with the molecular weight of the compounds or mixture of compounds treated. In one of its aspects the invention is directed particularly to the treatment of paraffinic hydrocarbon fractions produced in the primary distillation of petroleum oils.

Generally speaking, the isomeric or branched chain paraffin hydrocarbons are more reactive than the normal compounds and thus more capable of entering into various types of hydrocarbon reactions particularly reactions of alkylation in which alkyl groups are added to the molecules. In the case of normal butane, which occurs in relatively large percentages in the gases produced incidental to the production of petroleum and its primary distillation products and also in connection with cracking processes, there are normally more butanes than are required to furnish gasolines of the usual 10 pound Reid vapor pressure so that numerous processes have been developed to convert the excess of butanes into gasoline boiling range materials and thus increase the overall yield of gasoline obtainable from crude petroleum. Isobutane is readily alkylatable by normally gaseous olefinic hydrocarbons including ethylene, propylene and the butylenes to produce good yields of isomeric paraffins which have antiknock values corresponding to octane numbers well above 90 by the C. F. R. method. However, no processes have as yet been developed to a commercial point which permit the corresponding alkylation of normal butane so that one practical aspect of the present invention is immediately evident in that it effects the production of isobutane from the normal butane which is present in large quantities.

In the case of the normally liquid paraffin hydrocarbons of straight-chain structure, their anti-knock value uniformly increases with their degree of branching so that the highest antiknock values are generally exhibited by the compounds

of the most condensed molecular structure. In one aspect therefore, the present invention has practical value in increasing the antiknock value of individual paraffin hydrocarbons or similarly increasing the antiknock value of petroleum fractions in which low antiknock value paraffin hydrocarbons occur in substantial amounts such as gasolines or naphthas produced from paraffinic crudes.

10 In one specific embodiment the present invention comprises a process for the isomerization of normal or mildly branched paraffin hydrocarbons which consists in contacting them with metal halides of the Friedel-Crafts type, in the presence of hydrogen and hydrogen chloride, the amount of hydrogen being gradually decreased during the period of operation and the amount of hydrogen chloride being increased.

It is recognized that those skilled in the art 20 of hydrocarbon conversion are already conversant with the use of catalysts of the Friedel-Crafts type for the isomerization of hydrocarbons. Processes in present use, however, in contrast to the process of the present invention, ordinarily employ approximately fixed ratios of hydrocarbon, hydrogen chloride and hydrogen and operate at a substantially uniform temperature in continuous processes. In contrast to this, the present process starts out with relatively high 30 proportions of hydrogen to hydrogen chloride and moderate temperatures and maintains these conditions during a primary period of operation in which the catalyst has a relatively high activity. As the catalytic activity decreases due to unavoidable formation of metal halide complexes with hydrocarbon by-products the amount of hydrogen used is decreased while the amount of hydrogen chloride is increased. The effect of 35 decreasing the hydrogen is to compensate for the decreasing activity of the catalyst composite in two ways. From the first standpoint, as the catalyst activity decreases there will be a lessened tendency for undesirable side reactions other than isomerization to occur so that with small 40 amounts of hydrogen in admixture with the hydrocarbon undergoing treatment and assuming a constant rate of introduction of the hydrocarbon feed there will be a longer time of contact with the catalyst; and from the second standpoint, a larger amount of hydrogen present in the early stages of the processing period will lessen the amount of olefinic hydrocarbons produced due to the cracking of the catalyst composite so that there will be a small formation of metal halide-unsaturated hydrocarbon com-

plexes. An increase in the amount of hydrogen chloride as the hydrogen is decreased has always been found to exert a compensating influence in maintaining the activity of the metal halide catalysts so that by both decreasing hydrogen and increasing hydrogen chloride there is a definite lengthening of the catalyst life so that it is utilizable for longer periods of time without loss in activity below a practical point. As one means of varying the amount of hydrogen employed, it may be partially substituted by inert gases such as nitrogen, methane, ethane, or propane.

The improved features of operation which characterize the present invention are applicable to different types of processes in which metal halide catalysts are employed for isomerizing paraffin hydrocarbons. The simplest mode of operation which is applicable, particularly to the lower molecular weight normal paraffin hydrocarbons beginning with normal butane consists in passing the hydrocarbon either in liquid or vapor phase over a granular metal halide catalyst in fixed beds under conditions selected for optimum conversion. As a variation of this method the metal halides either singly or in various mixtures may be deposited upon relatively inert absorbent granular supports such as, for example, activated carbons, fuller's earth, clays of the bentonite or montmorillonite type either raw or acid treated, various refractory oxides such as prepared alumina, bauxite, magnesium oxide, etc., the supporting materials being preferably saturated with the metal halide. The third alternative method of operation may involve the use of molten metal halides or preferably molten mixtures of low fusing point through which the hydrocarbons to be isomerized are passed upwardly through a stationary pool. In all of these alternative processes the catalyst undergoes gradual deterioration and the process of the present invention is particularly applicable to stabilize the extent of isomerization over relatively long periods of time.

Catalysts of the Friedel-Crafts type include halides of such metals as aluminum, zirconium, zinc, tin, antimony, boron, etc., although it is recognized that they are not interchangeable in any given type of reaction and that all will not catalyze certain reactions. Of the compounds mentioned, aluminum chloride is generally the most applicable and zirconium chloride and zinc chloride follow in approximate order of decreasing activity. The eutectic mixtures which are

preferably used in accordance with the present invention may include combinations of any of the known catalysts of the Friedel-Crafts type which have any definite activity in isomerizing hydrocarbons and may also include corresponding compounds of other metals of lesser or substantially no activity such as, for example, compounds of titanium, hafnium, thorium, columbium, thallium, and the metals of the alkaline earth and alkali metal groups. Low melting mixtures of halides utilizable in the fluid condition can be formed by mixing proper proportions of chlorides which are distinctly of the Friedel-Crafts type or by mixing a chloride of this type with another chloride having substantially no activity in the desired reaction.

With regard to the conditions of temperature, pressure and flow which are optimum for effecting any desired isomerization according to the process of the invention, the combinations will evidently vary with the compound undergoing treatment and the particular mode of operation employed so that only broad ranges can be given. In general, temperatures of the order of from about 50 to about 200° C. may be employed and pressures from atmospheric to several hundred pounds per square inch. The temperature may be raised gradually during the processing period to compensate for the loss in catalytic activity. Flow rates will obviously vary with the particular type of operation employed as well as with the characteristics of the stocks charged.

The feature of the present invention consists in decreasing the amount of hydrogen employed while increasing the amount of hydrogen chloride during the processing period.

The following illustrative data are introduced to indicate the effects observed in isomerizing hydrocarbons in accordance with the present invention although the scope of the invention is not to be limited in exact correspondence therewith.

An aromatic-free hexane cut from a paraffinic petroleum having an octane number of 59 by the motor method was passed over a granular aluminum chloride catalyst under a pressure of 500 pounds per square inch at a liquid hourly space velocity of 0.15, hydrogen chloride being added to the reaction zone.

The following tabulation of data shows the effect of adding hydrogen in the initial stages of a run as compared with another run in which no hydrogen was added:

Run No.	Hrs. on-stream	H ₂ , moles/100 moles C ₆ H ₁₄	HCl, moles/100 moles C ₆ H ₁₄	Reactor block T., °C.	Prod., weight percent		Octane number hexane fraction
					Cr+Ca	Hexane fraction	
1-----	7	11	11	87-108	0.2	78.3	64.7
1-----	14	12	12	109	0.2	91.3	78.0
1-----	21	12	12	105	0.2	91.3	77.9
1-----	28	0	11	98	-----	1 (64)	-----
1-----	35	0	13	98	-----	1 (40)	-----
1-----	42	0	12	98	-----	1 (59)	-----
1-----	49	0	7-12	99	0.8	94.3	80.8
1-----	56	0	7-12	99	0.5	98.1	80.1
1-----	63	0	7-12	98	2.4	89.8	79.3
2-----	25	0	15	100	0.5	99+	73.8
2-----	49	0	15	100	2	92	73.8
2-----	65	0	15	100	3	91	73.8
2-----	92	0	15	100	0.5	99+	77.8
2-----	116	0	15	100	2	96	75.4
2-----	140	0	15	100	2	94	74.0
2-----	156	0	15	100	-----	90.5	76.9

¹ Low apparent yields because of gradual displacement of H₂ in system by hexane.

From the above data it is seen that in the absence of initially added hydrogen there is a rapid decrease in the amount of isomerization as the run progresses and that in Run 1 wherein hydrogen was added a relatively constant conversion was obtained during the initial period of hydrogen addition and that the conversion and octane number was maintained after the hydrogen feed had been discontinued.

I claim as my invention:

1. A process for the isomerization of a paraffin hydrocarbon to produce more highly branched isomers therefrom which comprises contacting said hydrocarbon mixed with hydrogen and a hydrogen halide with a metal halide isomerizing catalyst of the Friedel-Crafts type for a period of time corresponding to a desired production of said isomers, the amount of hydrogen mixed with said hydrocarbon being gradually reduced and the amount of hydrogen halide mixed with said hydrocarbon being gradually increased during said period.

2. A process for the isomerization of a paraffin hydrocarbon to produce more highly branched isomers therefrom which comprises contacting said hydrocarbon mixed with hydrogen and hydrogen chloride with a granular mass comprising a metal chloride isomerizing catalyst of the Friedel-Crafts type as its principal active constituent, for a period of time corresponding to a desired production of said isomers, the amount of hydrogen mixed with said hydrocarbon being gradually reduced and the amount of hydrogen chloride mixed with said hydrocarbon being gradually increased during said period.

3. A process for the isomerization of a paraffin hydrocarbon to produce more highly branched isomers therefrom which comprises contacting said hydrocarbon mixed with hydrogen and a hydrogen halide with a fluid mass of metal halide isomerizing catalyst of the Friedel-Crafts type as its principal active constituent, for a period of time corresponding to a desired production of said isomers, the amount of hydrogen mixed with said hydrocarbon being gradually reduced and the amount of hydrogen halide mixed with said hydrocarbon being gradually increased during said period.

4. A process for the isomerization of a paraffin hydrocarbon to produce more highly branched isomers therefrom which comprises contacting said hydrocarbon mixed with hydrogen and hydrogen chloride with a fluid mass of metal chloride isomerizing catalyst of the Friedel-Crafts type as its principal active constituent, for a period of time corresponding to a desired production of said isomers, the amount of hydrogen mixed with said hydrocarbon being gradually reduced and the amount of hydrogen chloride mixed with said hydrocarbon being gradually increased during said period.

5. A process for the isomerization of paraffin hydrocarbons of straight-chain structure to produce more highly branched isomers therefrom which comprises contacting said hydrocarbon mixed with hydrogen and hydrogen chloride with a metal halide isomerizing catalyst of the Friedel-Crafts type for a period of time corresponding

to a desired production of said isomers, the amount of hydrogen mixed with said hydrocarbon being gradually reduced and the amount of hydrogen chloride mixed with said hydrocarbon being gradually increased during said period.

6. A process for the isomerization of paraffin hydrocarbon of straight-chain structure to produce more highly branched isomers therefrom which comprises contacting said hydrocarbon mixed with hydrogen and hydrogen chloride with aluminum chloride for a period of time corresponding to a desired production of said isomers, the amount of hydrogen mixed with said hydrocarbon being gradually reduced and the amount of hydrogen chloride mixed with said hydrocarbon being gradually increased during said period.

10 7. A process for converting paraffins into more highly branched isomers which comprises subjecting the paraffins under isomerizing conditions to the action of a metal halide isomerizing catalyst of the Friedel-Crafts type in the presence of hydrogen and a hydrogen halide, and, as the activity of the catalyst decreases and during the contacting therewith of paraffins being isomerized, reducing the proportion of hydrogen and increasing the proportion of hydrogen halide with respect to the amount of paraffins undergoing treatment.

15 8. A process for converting paraffins into more highly branched isomers which comprises subjecting the paraffins under isomerizing conditions to the action of a metal halide isomerizing catalyst of the Friedel-Crafts type in the presence of hydrogen and a hydrogen halide, and reducing the ratio of hydrogen to paraffins and increasing the ratio of hydrogen halide to paraffins as the activity of the catalyst decreases during the contacting of paraffins therewith.

20 9. A process for converting paraffins into more highly branched isomers which comprises adding hydrogen and a hydrogen halide to a stream of the paraffins, contacting the resultant mixture under isomerizing conditions with a metal halide isomerizing catalyst of the Friedel-Crafts type, and, as the activity of the catalyst decreases, reducing the hydrogen-paraffin ratio and increasing the hydrogen halide-paraffin ratio in said stream.

25 10. A process for converting paraffins into more highly branched isomers which comprises adding hydrogen and a hydrogen halide to a stream of the paraffins, contacting the resultant mixture under isomerizing conditions with a metal halide isomerizing catalyst of the Friedel-Crafts type, and, as the activity of the catalyst decreases, reducing the amount of hydrogen and increasing the amount of hydrogen halide added to said stream.

30 11. The process as defined in claim 8 further characterized in that said catalyst comprises aluminum chloride and the hydrogen halide is hydrogen chloride.

35 12. The process as defined in claim 9 further characterized in that said catalyst comprises aluminum chloride and the hydrogen halide is hydrogen chloride.

HERMAN S. BLOCH.
